[57] CLAIM

The ornamental design for candle extinguisher or the like, as shown and described.

DESCRIPTION

FIG. 1 is a top, front perspective view of a candle extinguisher or the like showing my new design;

FIG. 2 is a left side elevational view thereof;

FIG. 3 is a top plan view thereof;

FIG. 4 is a rear elevational view thereof;

FIG. 5 is a front elevational view thereof;

FIG. 6 is a bottom plan view thereof;

FIG. 7 is a top, front perspective thereof in the open position;

FIG. 8 is a right side elevational view thereof in the open position, a candle being shown in broken lines for illustrative purposes only.
